United States Patent Office

Des. 185,030
Patented Apr. 28, 1959

185,030

JEWELRY FINDING OR SIMILAR ARTICLE

Samuel J. McCormick, Attleboro, Mass., assignor to
Metals & Controls Corporation, Attleboro, Mass., a
corporation of Massachusetts

Application April 9, 1957, Serial No. 45,654

Term of patent 14 years

(Cl. D45—1)

Fig. 1.

Fig. 4.

Fig. 3.

Fig. 2.

Fig. 1 is a plan view of a jewelry finding embodying my design;

Fig. 2 is a front elevational view thereof;

Fig. 3 is a side elevational view thereof; and

Fig. 4 is an elevational view taken at an angle substantially midway between those of Figs. 2 and 3.

Portions of the drawing have been stippled to indicate contrast.

I claim:

The ornamental design for a jewelry finding or similar article, substantially as shown and described.
